United States Patent Office

Des. 198,593
Patented July 7, 1964

198,593

BOTTLE

Stanley K. Johns, P.O. Box 338, Adelaide St. Post Office,
Toronto, Ontario, Canada

Filed Aug. 16, 1963, Ser. No. 76,241

Term of patent 7 years

(Cl. D58—8)

Fig. 3

Fig. 1

Fig. 2

FIG. 1 is a front elevational view of a bottle embodying my new design;

FIG. 2 is a side elevational view thereof; and

FIG. 3 is a top plan view thereof.

I claim:

The ornamental design for a bottle, as shown.
